UNITED STATES PATENT OFFICE.

HARRY LEONARD WAITE, OF EGREMONT, ENGLAND.

SOUNDING-MACHINE.

1,094,763.

Specification of Letters Patent. Patented Apr. 28, 1914.

Application filed December 20, 1913. Serial No. 802,001.

To all whom it may concern:

Be it known that I, HARRY LEONARD WAITE, a subject of the King of Great Britain, and residing in Egremont, in the county of Chester, England, have invented certain new and useful Improvements in and Relating to Sounding-Machines, of which the following is a specification.

The present invention relates to sounding machines of the type in which a cord or cable, attached to the lead or sounding device, is wound upon a rotatable drum provided with operative means and a frictional device, by means of which the drum can be allowed to run so as to pay out the cable under the pull of the lead, or alternatively, the drum can be rotated so as to hoist the lead. Such machines are usually provided with an indicating device whereby the length of cable unwound from the drum is shown, and the object of the present invention is to provide an improved indicating device for sounding machines of the type referred to.

I have illustrated a sounding machine embodying my invention in the accompanying drawings, in which—

Figure 1 is a front elevation in part section, Fig. 2 is a side elevation, Fig. 2^a is a view of the upper end of bar H showing more plainly its graduations h². Fig. 3 is a plan, and Fig. 4 is a detail view of a modification of the indicating device. Fig. 4^a is a side and end view of bar H showing the location of graduations h².

The sounding machine illustrated, which is selected as a typical form in order to show the application of my present invention to machines generally of this kind, forms the subject matter of my concurrent application for a patent of the United States, Serial No. 782320, and the construction may be described briefly, so far as is necessary in order to understand the application of my present invention, as follows:—

The cable or cord carrying drum A is mounted loosely on the shaft B carried in bearings on the main frame C. The shaft may be rotated at will in the direction which hoists the lead by handles applied to the squared ends b⁵ and b⁶, or by the electromotor M with its controller m¹, through the train of spur wheels m³, m⁴ and b¹, of which m⁴ is mounted slidably on the stud m⁵ so as to be disengageable.

b² is a ratchet wheel fitted on the end of

the shaft B and provided with a holding pawl b³ which prevents the shaft from turning in the direction which lowers the lead.

D and e¹ are friction flanges feathered on the shaft B on opposite sides of the drum A and adapted by axial pressure to frictionally couple the drum to the shaft, this pressure being applied by the hand wheel F screwing on the end of the shaft B and engaging with the end of the sleeve E, which is integral with the flange e¹. This sleeve is journaled in the main frame C and itself forms a bearing for the shaft B.

It will be understood that when lowering the lead, the shaft B is held by its ratchet wheel b², and the frictional grip is relaxed and regulated by the hand wheel F so as to allow the cable to run out at a suitable speed or to arrest it at will. In order to hoist the lead, the drum and shaft are coupled with a sufficient grip by screwing up the wheel F, and the shaft is then rotated by hand or by the electromotor.

The indicating device, which forms the subject matter of the present application, comprises an indicating bar H mounted so that it can slide axially in the main frame C, and gearing articulating the bar to the drum so that the lineal movement of the bar is proportional to the number of revolutions made by the drum.

A worm screw G, (see Figs. 1 and 3), is mounted freely on the shaft B, and is rotated by means of the cranked arm g which engages with a hole in the side of the drum A.

A worm wheel g¹, Fig. 2 mounted on a vertical shaft g² arranged at right angles to the shaft B gears with the worm screw G. The shaft g², mounted in a bottom bracket g³ and a top bracket g⁴ suitably carried from the main frame C, has fitted at its upper end a bevel spur wheel g⁵ gearing with a bevel spur wheel h¹ fixed to one end of a spindle h²; the other end of this spindle carries a gear wheel h which gears with rack teeth cut on the bar H. The bar H which is arranged to protrude through its guide h³ carried by the main frame will obviously indicate by its position the length of cable unwound from the drum and it is graduated accordingly as shown at h²; in addition to graduation marks adapted to be read visually, the bar is made with notches or projections at various points along its length, so that the length of cable unwound may be

ascertained, even in the dark, by passing the hand along the part of the bar which protrudes, and feeling and counting the number of notches or projections so exposed.

5 In addition to giving the length of cable paid out when the lead is lowered, the indication afforded is a guide to the operator in hoisting so that he may not over-wind the cable.

10 The provision of graduations which can be felt has the advantage that the indication can be ascertained under weather conditions which might render it inconvenient to inspect a dial, or even during darkness which would otherwise necessitate a lamp.

15 The bar H' is preferably made comparatively massive, as it is found to be useful in resisting sudden changes in the speed of the drum, in paying out the cable, due to the 20 rising and falling of the ship; when the ship rises, the increased drag of the descending lead tends to accelerate the drum, which may then overrun the cable when the ship descends, thus risking fracture of the 25 cable. The inertia effect of the comparatively massive indicating bar H' , in conjunction with the considerable friction resistance in the transmission due to the worm drive, has a steadyng tendency on the drum, and reduces the risk of losing the lead by 30 fracture of the cable.

In the modification shown in Fig. 4, a 35 screwed bar H' is provided in place of the toothed rack bar H . The screwed bar H' is carried in suitable guides and a fixed pin h'' , engaging in a groove h'' in the rod H' , prevents the latter from turning but allows it to slide freely up and down. A gear 40 wheel h' rotatably mounted in the bracket g'' forms a nut for the rod H' , and a

screwed extension on the boss of the gear wheel h' is fitted with the nut h'' which bears against the under side of the bracket g'' and prevents axial movement of the wheel h' . The gear wheel h' gears with another gear wheel g'' fixed to the upper end of the shaft g'' , which is geared to the drum A as before described. 45

It is obvious that the bar H' will, as in the case of the bar H , indicate by the length 50 of it which protrudes, the amount of cable unwound from the drum, and it is notched, as in the case of the bar H , or the screw threads themselves may afford the necessary indications adapted to be counted by the 55 sense of touch.

Having now fully described my invention, I declare that what I claim, and desire to secure by Letters Patent is:—

In a sounding machine comprising in combination a frame, a main shaft, a cable drum loosely mounted thereon and having a cable positively attached thereto, means for driving said cable drum, a notched indicating bar adapted to protrude through said frame and adapted to move axially thereto, a worm gear rotationally mounted on said shaft and positively coupled with said drum to be driven thereby, and reduction gear interposed between said worm gear and said 70 notched bar adapted to move the latter axially in a direction corresponding to the direction of rotation of said drum, substantially as described.

In testimony whereof I affix my signature 80 in presence of two witnesses.

HARRY LEONARD WAITE.
